CLAIM

The ornamental design for a bathroom cabinet, as shown and described.

DESCRIPTION

FIG. 1 is a front elevational view of my bathroom cabinet showing my new design;

FIG. 2 is a side view thereof;

FIG. 3 is a top view thereof; and

FIG. 4 is a rear elevational view thereof.

The side and bottom of the cabinet not shown are the same as FIGS. 2 and 3, respectively.
